FLOOR POLISHING ATTACHMENT FOR VACUUM CLEANERS

Filed Jan. 10, 1927

Inventor:
Henry T. Lang,
by *Henry T. Lang*
His Attorney.

UNITED STATES PATENT OFFICE.

HENRY T. LANG, OF CLEVELAND, OHIO, ASSIGNOR TO ELECTRIC VACUUM CLEANER COMPANY, INC., OF CLEVELAND, OHIO, A CORPORATION OF NEW YORK.

FLOOR-POLISHING ATTACHMENT FOR VACUUM CLEANERS.

Application filed January 10, 1927. Serial No. 160,209.

It has been the practice for many years for manufacturers of vacuum cleaners to supply with their products some form of attachment for cleaning and polishing floors, usually in the form of a shoe which was detachably secured to the underside or mouth of the nozzle. In some instances the polishing device moved only as the cleaner itself was moved, while in others it was moved or actuated by the cleaner motor also and hence had two movements. The success or failure of these devices when used in the home is dependent upon how well they will polish and how readily they may be applied to and removed from the cleaner. If they cannot be easily and quickly applied to and removed from the cleaner the average person will not use them, no matter how well they polish.

My invention has for its object to provide a floor-polishing device of improved construction for vacuum cleaners, which takes the form of an attachment for such cleaners and one which can be easily and quickly applied to and removed from the underside of a cleaner nozzle and which will effectively polish hardwood floors.

For a consideration of what I believe to be novel and my invention, attention is directed to the accompanying description and the claims appended thereto.

In the accompanying drawing which is illustrative of my invention, Fig. 1 is a perspective view of a vacuum cleaner fitted with my improved floor-polishing brush; Fig. 2 is a perspective view of the brush-supporting frame; Fig. 3 is a detail view, partly in section, of the cleaner nozzle and brush; Fig. 4 is a sectional view of one of the brush bearings and ratchet; Fig. 5 is a sectional view of the ratchet means for preventing backward rotation of the brush; Fig. 6 is a detail view of the brush-driving means; Fig. 7 is a modified form of ratchet or clutch means, and Fig. 8 is a detail, sectional view through the end of the brush frame.

I have chosen to illustrate my invention in connection with a well-known type of vacuum cleaner now on the market in which 10 indicates the electric motor for driving the suction fan 10^a which is contained in the casing 11, and 12 the nozzle. The cleaner is supported by a single wheel or castor 13, at the rear and by a pair of floor wheels 14, at the front. The wheels 14 are mounted on

pivots carried by the U-shaped frame or 55 member 15, the latter being supported by two pivots 16 at the front end. The wheels are adjusted up and down to change the clearance between the lips of the nozzle and the surface to be cleaned by the adjusting 60 screw 17, which is threaded into a boss formed on the rear of the nozzle. The lower end of the screw has a reduced portion 18 which enters a slot in a lip 19 carried by the member 15. Turning the screw raises or 65 lowers the wheels, depending upon the direction of movement. The cleaner is moved over the floor by a handle of which the bail portion is shown. The dust-laden air from the nozzle passes through the fan and 70 is discharged through the outlet 20, the latter normally being connected to a dust bag as is usual in such cases.

21 indicates a frame for the polishing brush 22 which latter may be of any approved construction having bristles which are stiff enough to support the front end of the cleaner. The frame which is rectangular has front, rear and end members. The end members carry ball bearings for the 80 brush, one of which is shown in section in Fig. 4. Extending across the frame are two flat straps 23 which firmly engage the underside of the front and rear lips 24 of the nozzle, as best shown in Fig. 3. On the 85 straps are vertically-extending lugs 25 which engage the end lips of the nozzle and thus prevent the frame from moving endwise with respect thereto. The lugs are relatively long and being in frictional engagement with the inner edges of the ends of the nozzle assist in preventing movements of the brush frame cross-wise of the nozzle. To fasten the frame to the nozzle, two pivotally-attached stirrups 26 are provided, one 90 at each end. The stirrups are of such size as to partially embrace the floor wheels 14 as shown in Figs. 1 and 3. In applying the 95 polishing brush the floor wheels are first lowered by turning the screw 17 to permit 100 the stirrups to be slipped over them, after which the screw is turned in the opposite direction until the straps 26 firmly contact with the lips of the nozzle and the stirrups are seated on the upper portions of the 105 wheels. The wheel-carrying lever 15 and the screw 17 are capable of exerting a very substantial leverage and in a simple manner

with the result that the brush frame and nozzle are firmly united and hence are able to withstand the strains to which they are subjected in service.

- 5 In order to rotate the brush it is provided with a pulley 27 which is driven by a quarter turn belt 28 made of rubber from the pulley 29, the latter being on the front end of the armature shaft 30 of the motor 10. When 10 the cleaner is originally provided with a rotary brush which is located within the nozzle itself and is driven by a quarter turn rubber belt by the motor shaft, I utilize the same pulley and belt for driving the polishing brush, first removing the dirt-agitating brush from within the nozzle. If the cleaner nozzle has no such brush, provision is made for driving the polishing brush by prolonging the armature shaft and mounting 20 a pulley thereon; the structure will then be the same as that shown in Fig. 1 and in Fig. 6.

When the floor-polishing brush is in use there is no need for the suction fan and 25 to substantially decrease the load on the motor at such times I close the passage through the fan casing. This is a well-understood feature of construction in centrifugal compressors. As the simpler construction is to close the outlet, a cap 31 is provided which is fastened over the outlet 20, the dust bag having been first removed. Under these conditions, the loss of power due to the fan is represented by the windage 35 or eddy current losses of the fan.

In a construction of this character involving as it does a rubber belt, usually one having a quarter turn, it is important to prevent the reverse rotation of the brush which 40 movement is practically certain to throw the belt off of one or both of the pulleys. To prevent this, a suitable ratchet is provided which permits the brush to revolve freely in one direction but not in the other, for example, when the cleaner and polisher are 45 given forward and backward strokes by the user. A suitable ratchet is shown in Figs. 4 and 5 and comprises a cylindrical center member 32, one or more wedge shaped cam 50 surfaces 33 and an equal number of hard steel balls 34. A mounting for the parts is shown in Fig. 4 wherein 35 is a thin, metal container at one end of which the cam surfaces 33 are formed. Seated on a shoulder 55 within the sleeve is a ball bearing comprising an outer ball race, the balls running in a groove in the stub shaft 36 on which the cylindrical portion 32 is also formed. The stub shaft is clamped in place on the downwardly-extending ear 37 of the brush frame 60 by the nut 38. Grease or other lubricant for the bearing is retained by a felt washer and its supporting cap. The opposite end of the polishing brush does not require a 65 ratchet but it is provided with a ball bear-

ing of the construction shown in Fig. 4. For convenience in mounting, the outer or exposed end of the stub shaft of this second bearing is provided with two flat sides to prevent it from turning and the shaft end 70 is located in a downwardly-opening slot 39 as shown in Fig. 2. If desired, the stub shaft which cooperates with the clutch may have other means to prevent it from turning in the frame instead of utilizing the nut 38. 75 One end of the brush, however, is preferably held by a nut. When not in use the tension of the belt 28 is sufficient to hold this end of the brush in place, and when the polisher is in use the weight of the parts is 80 sufficient.

In Fig. 7 is shown a modified form of ratchet or clutch for the brush. It differs principally from the one shown in Fig. 5 in that rollers 40 are substituted for the balls 85 34, and instead of depending upon centrifugal force to seat them a light spring 41 is employed for the purpose. Each spring is held in position at its outer end by a projection 42 on the surrounding member and 90 on its inner end directly engages a roller. By preference, both the rollers and the surfaces engaged thereby are hardened to reduce wear.

Fastened to the ends of the frame are 95 suitable rubber bumpers 46 held in place by metal rivets 47, the heads of the rivets being embedded in the rubber. The purpose of these rubber bumpers is to prevent marring the wainscoting as the side of the polisher 100 is run along it.

In operating the polisher, the circuit of the motor is first closed which causes the brush to revolve, after which the polisher is moved back and forth over the floor by 105 means of the handle. I may support the apparatus by the brush at the front end and the floor wheel 13 at the rear, or I may clamp the handle bail by the wing nut 43 on the segment 44 in such position that the 110 apparatus is supported on the floor by the brush only, the hand of the operator sustaining the balance of the weight at the rear. In the latter case, the effective downward pressure on the brush is somewhat 115 greater than in the former case.

When it is desired to use the vacuum cleaner as such the polishing brush is removed by reversing the above-stated operations. If the cleaner is of the type having 120 a revolving dirt-agitating brush the brush is mounted in place and belted to the armature shaft. To facilitate mounting the belt in place on the motor shaft pulley, both when used as a cleaner and as a polisher, the 125 front end of the nozzle is provided with an opening of suitable size and a removable cover plate 45.

In accordance with the provision of the patent statute, I have described the principle 130

of operation of my invention, together with the apparatus which I now consider to represent the best embodiment thereof; but I desire to have it understood that the apparatus shown is only illustrative and that the invention may be carried out by other means.

What I claim as new and desire to secure by Letters Patent of the United States, is:—

10 1. A floor polishing attachment for use with a vacuum cleaner having a nozzle, a motor, and floor-engaging wheels, said attachment comprising a polishing brush, a supporting frame therefor, members carried by the frame which engage the wheels to hold the frame against the nozzle, and a belt driven by the motor for rotating the brush.

2. A floor polishing attachment for use with a vacuum cleaner having a nozzle and a motor, said attachment comprising a rotating polishing brush, a supporting frame therefor, means for clamping the frame to the underside of the nozzle, a belt driven by the motor for rotating the brush, and means for preventing the reverse rotation of the brush as the cleaner is moved backward by the operator.

3. A floor polishing attachment for use with a vacuum cleaner having a nozzle, a motor and floor wheels which normally support the nozzle, said attachment comprising a rotary brush which rests on the surface to be polished and supports the front end of the cleaner, a frame in which the brush is mounted, stirrups which are carried by the frame and partly encircle the floor wheels and hold the frame against the nozzle walls, and a belt driven by the motor for rotating the brush.

4. A floor polishing attachment for use with a vacuum cleaner having a nozzle, a motor, floor wheels, a pivoted member on which the wheels are supported, and means for moving the frame to adjust the wheels, said attachment comprising a rotary polishing brush, a supporting frame therefor, devices carried by the frame which engage the wheels to clamp the frame against the under surface of the nozzle, and a belt which transmits motion from the motor to the brush.

5. A floor polishing attachment for use with a vacuum cleaner having a nozzle, a motor and floor wheels, said attachment comprising a rotary brush which rests on the surface to be polished, a frame for supporting the brush which has members that are arranged to be seated on the underside of the nozzle, means which engage the floor wheels and cause the members to be firmly

clamped against the nozzle, and means for rotating the brush.

6. A floor polishing attachment for use with a vacuum cleaner having a nozzle, a motor and floor wheels, said attachment comprising a rotary brush which rests on the surface to be polished, a rectangular frame for supporting the brush, cross members on the frame which are arranged to be seated on the underside of the nozzle, means also carried by the frame which engage the ends of the nozzle to prevent endwise movement of the frame, stirrups which partly enclose the floor wheels to hold the frame against the nozzle, and a belt for driving the brush from the motor shaft.

7. A floor polishing attachment for use with a vacuum cleaner having a nozzle, floor-supporting wheels and an adjustable, pivoted member which carries the wheels, said attachment comprising a polishing brush, a supporting frame therefor, and pivoted stirrups which are carried by the frame and are adapted to partly encircle the wheels and hold the frame in position when the floor wheels are adjusted to engage the stirrups.

8. A floor polishing attachment for use with a vacuum cleaner having a nozzle, a suction device and a motor, said attachment comprising a frame, means for detachably securing the frame to the cleaner, a rotary polishing brush mounted in bearings on the frame, a driving connection between the motor and brush, means for preventing backward rotation of the brush due to movements of the cleaner, and means for reducing the power consumed by the suction device when the polishing brush is in use.

9. A floor polishing attachment for a vacuum cleaner having a nozzle, a member pivoted on the nozzle and means for adjusting said member vertically, said attachment comprising a rotary polisher, bearings for the polisher, supporting means for the bearings which are moved by the member to clamp the polisher to the nozzle, and means for rotating the polisher.

10. A floor polishing attachment for a vacuum cleaner having a nozzle, a member pivoted on the nozzle and an adjusting screw for the member, said attachment comprising a rotary polisher, bearings for the polisher, supporting means for the bearings which are moved by the member and adjusting screw to clamp the polisher to the underside of the nozzle, and means for rotating the polisher.

In witness whereof, I have hereunto set my hand.

HENRY T. LANG.
